(57) **CLAIM**

We claim the ornamental design for an animal footbath, as shown and described.

DESCRIPTION

FIG. 1 is a top perspective view of an embodiment of an animal footbath showing our new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof; and

FIG. 7 is a rear elevational view thereof;

FIG. 8 is a top perspective view of another embodiment of an animal footbath showing our new design;

FIG. 9 is a top plan view thereof;

FIG. 10 is a right side elevational view thereof;

FIG. 11 is a left side elevational view thereof;

FIG. 12 is a bottom plan view thereof;

FIG. 13 is a front elevational view thereof; and

FIG. 14 is a rear elevational view thereof;

FIG. 15 is a top perspective view of another embodiment of an animal footbath showing our new design;

FIG. 16 is a top plan view thereof;

FIG. 17 is a right side elevational view thereof;

FIG. 18 is a left side elevational view thereof;

FIG. 19 is a bottom plan view thereof;

FIG. 20 is a front elevational view thereof; and

FIG. 21 is a rear elevational view thereof;

FIG. 22 is a top perspective view of another embodiment of animal footbath showing our new design;

FIG. 23 is a top plan view thereof;

FIG. 24 is a right side elevational view thereof;

FIG. 25 is a left side elevational view thereof;

FIG. 26 is a bottom plan view thereof;

FIG. 27 is a front elevational view thereof; and,

FIG. 28 is a rear elevational view thereof.

(Continued)

In the drawings, the peripheral broken lines depict portions of the animal footbath that form no part of the claimed design.
